UNITED STATES PATENT OFFICE.

JOSEPH J. BODY, LEE LONG, AND MASON L. JOHNSON, OF DANTE, AND CHARLES F. KILGORE AND ALONZO BLEVINS, OF COEBURN, VIRGINIA.

MINE-DOOR-OPERATING MEANS.

1,311,488.

Specification of Letters Patent. Patented July 29, 1919.

Application filed January 16, 1919, Serial No. 271,452.

To all whom it may concern:

Be it known that we, JOSEPH J. BODY, LEE LONG, and MASON L. JOHNSON, citizens of the United States, residing at Dante, in the county of Russell and State of Virginia, and CHARLES F. KILGORE and ALONZO BLEVINS, citizens of the United States, residing at Coeburn, in the county of Wise and State of Virginia, have invented certain new and useful Improvements in Mine-Door-Operating Means; and we do declare the following to be a full, clear, and exact description of the invention, such as will enable others skilled in the art to which it appertains to make and use the same.

Our invention relates to improvements in mine door operating mechanisms such as disclosed in United States Patent #1,255,697, of February 5, 1918, granted to J. J. Body, M. L. Johnson, C. F. Kilgore, and A. Blevins, the object of the present invention being to simplify the mechanism in such a manner as to obtain equally good results with considerably less parts.

With the foregoing in view, the invention resides in the novel features of construction and unique organization of parts hereinafter fully described and claimed.

Figure 1 of the accompanying drawings is a top plan view of a mine track and the door operating means, showing the doors in horizontal section.

Fig. 2 is a side elevation of the parts disclosed in Fig. 1.

Fig. 3 is a detail perspective view of one of the door opening rods and its respective slide.

Fig. 4 is an enlarged top plan view of a portion of the door opening means.

Fig. 5 is a sectional view as indicated by the line 5—5 of Fig. 4.

Fig. 6 is a view similar to Fig. 4 but indicating the relative positions of parts when the doors are opened.

Fig. 7 is a vertical transverse section on the plane of the line 7—7 of Fig. 1.

In the drawings above briefly described, a mine track is shown passing through a tunnel 1 and consisting of rails 2, and ties 3, a depressible car-operated member being provided of the same construction and operation as disclosed in the patent above referred to, said member consisting of main

horizontal depressible rails 4, inclined end rails 5, and transverse bridle bars 6 connecting the several rails. Links 7 depend from the ends of the rails 4 and are pivoted to crank arms 8 on transverse rock shafts 9 which are mounted in suitable bearings below the rails, the ends of said rock shafts being provided with upstanding crank arms 10.

All of the features so far described are disclosed in the aforementioned patent and need not therefore be entered into with further detail, but it may be well to point out that the crank arms 8 of one shaft converge upwardly with respect to those of the other shaft and that this arrangement causes turning of the two shafts in a clockwise manner when a car approaches in one direction, and counter-clockwise when the car is traveling in the opposite direction; and on account of the arrangement yet to be specified the horizontally swinging doors 11 are opened in the direction in which the car is traveling.

A pair of longitudinal door opening members 12 extend longitudinally along opposite sides of the track and at their ends are pivoted to the crank arms 10. The two members 12 and associated parts are of identical construction, and only the parts at one side of the track will therefore be described in detail, although the same reference characters are applied to the features at the other side of said track.

Member 12 consists of a central slide bar 13 and oppositely extending longitudinal rods 14 secured thereto in a preferred manner, said slide bar being shown as provided with lugs 15 through which the inner ends of the rods 14 pass, nuts 16 being threaded on said rods in contact with opposite sides of the lugs. By this arrangement, any necessary adjustments in the length of the door opening member 12 may be easily made. The outer edge of the slide bar 13 is provided with gear teeth 17 meshing with a pinion 18 carried by the lower end of the vertical shaft 19 which carries one of the door sections 11. It will thus be seen that when the member 12 is shifted by rocking of the shafts 9, due to depression of the rails 4 and 5, the doors will be opened in the direction in which the car is traveling. Under normal circumstances, the doors must

remain closed and for obtaining this result, permitting opening of said doors when required, and again closing them after passage of the car, the following provision is made.

A pair of coiled springs 20 are mounted on the inner end portions of the rods 14 and the outer ends of these springs bear against adjustable collars 21 on said rods, the inner ends of said springs, however, resting against slides 22 which are preferably in the form of T-shaped metal keys received in longitudinal slots 23 formed in the rods 14, said slides being normally located at the inner ends of the slots 23 as seen in Figs. 4 and 5, and then bearing against fixed abutments 24 through which the inner ends of the rods 14 may slide. The abutments 24 may be of any preferred form, but they are preferably constructed by bending the ends of a longitudinal bar 25 as shown, said bar being secured to the upper side of one of the ties 3 and being braced thereto at 26.

By the arrangement of springs, slides, collars and abutments above described, both springs normally exert their tension to hold the members 12 in a neutral position, thereby holding the doors closed. When the members 12 are shifted in either direction, however, the doors are opened and two of the springs come into play against their respective abutments, while the other springs move away from the abutments against which their slides 22 were normally engaged (see Fig. 6). By this mode of operation, the compressed springs return the several parts to their initial positions, unretarded by the other springs, since the latter have not been compressed. Allowing only one set of springs to come into play when the door is opened, is also of advantage since it prevents excessive operation of the springs and possible weakening thereof.

The doors 11 may, of course, be of any adequate construction but they are preferably provided with glass covered view openings 27. The space at one side of the doors is preferably closed by boards or the like 28 (Fig. 7), while a door 29 is provided at the opposite side of the track to permit miners and other workmen to travel through the tunnel without opening the doors 11.

From the foregoing, taken in connection with the accompanying drawings, it will be seen that we have greatly simplified the door operating mechanism shown in the patent above referred to, yet that no advantages have been sacrificed by such simplification. In fact, the present invention is of great advantage over the prior device, due to its reduced cost, ease of operation and economy of upkeep.

Since probably the best results are obtained from the details shown and described, they may be followed if desired, but within

the scope of the invention as claimed, considerable latitude is allowed for making numerous minor changes.

What we claim is:

1. In combination with a door adapted to extend across a roadway, car-operated means adapted for disposition on said roadway, a longitudinal door-opening member, connecting means between said door-opening member and door for opening the latter in either direction, means for sliding said door-opening member in either direction upon operation of said car-operated means, according to the direction in which the car is traveling along the roadway, a pair of coiled springs mounted on said door-opening member and having one end arranged for movement bodily therewith, slides against which the other ends of said springs bear, said slides being carried by said door-opening member, and abutments against which said slides bear, said abutments being fixed with respect to said door-opening member; one slide being movable away from its respective abutment when the door-opening member slides in one direction and said member then moving with respect to the other slide, and vice versa.

2. In combination with a door adapted to extend across a roadway, car-operated means adapted for disposition on said roadway, a longitudinal door-opening member, connecting means between said door-opening member and door for opening the latter in either direction, means for sliding said door-opening member in either direction upon operation of said car-operated means, according to the direction in which the car is traveling along the roadway, a pair of coiled springs mounted on said door-opening member and having one end arranged for movement bodily therewith, slides against which the other ends of said springs bear, said door-opening member having slots receiving said slides, the latter normally resting at one end of said slots, and abutments against which said slides bear, said abutments being fixed with respect to said door-opening member; one slide being movable away from its respective abutment when the door-opening member slides in one direction and said member then moving with respect to the other slide, and vice versa.

3. In combination with a door adapted to extend across a roadway, car-operated means adapted for disposition on said roadway, a longitudinal door-opening member, connecting means between said door-opening member and said door for opening the latter in either direction, means for sliding said door-opening member in either direction upon operation of said car-operated means, according to the direction in which the car is traveling along the roadway, a pair of springs devices located at spaced points on said

door-opening member, one end of said spring devices being mounted for movement bodily with said door-opening member and the other ends of said spring devices being slid-
5 able on said door-opening member, and abutment means against which said slid-
able ends of said spring devices bear, said abut-
ment means being fixed with respect to said
door-operated member; each spring device
10 being movable away from said abutment
means when said door-opening member
slides in a direction to compress the other
spring device.

4. In combination with a door adapted to
15 extend across a roadway, car-operated means
adapted for disposition on said roadway, a
longitudinal door-opening member, connect-
ing means between said door-opening mem-
ber and door for opening the latter in either
20 direction, means for sliding said door-open-
ing member in either direction upon opera-

tion of said car-operated means, according
to the direction in which the car is traveling
along the roadway, abutment means with re-
spect to which said door-opening member
25 slides, shoulders on said door-opening mem-
ber spaced from said abutment means, and
spring devices mounted on said door-open-
ing member between said abutment means
and said shoulders, one of said spring de-
30 vices being compressed when the door-open-
ing member slides in one direction and the
other spring device being similarly com-
pressed when said member slides in the other
direction.

In testimony whereof we have hereunto
set our hands.

JOSEPH J. BODY.
LEE LONG.
MASON L. JOHNSON.
CHARLES F. KILGORE.
ALONZO BLEVINS.
